US00D956091S

(12) **United States Design Patent** (10) **Patent No.:** **US D956,091 S**
(45) **Date of Patent:** **** Jun. 28, 2022**

(54) **DISPLAY SCREEN OR PORTION THEREOF WITH ICON**

(71) Applicant: **Apple Inc.**, Cupertino, CA (US)

(72) Inventors: **Aurelio Guzmán**, San Jose, CA (US);
Christopher Wilson, San Francisco, CA (US)

(73) Assignee: **Apple Inc.**, Cupertino, CA (US)

(**) Term: **15 Years**

(21) Appl. No.: **29/708,496**

(22) Filed: **Oct. 7, 2019**

Related U.S. Application Data

(63) Continuation of application No. 29/674,420, filed on Dec. 21, 2018, now Pat. No. Des. 862,515, which is a continuation of application No. 29/649,070, filed on May 25, 2018, now Pat. No. Des. 836,671, which is a continuation of application No. 29/606,371, filed on Jun. 4, 2017, now Pat. No. Des. 819,077.

(57) **CLAIM**

The ornamental design for a display screen or portion thereof with icon, as shown and described.

DESCRIPTION

The FIGURE is a front view of a display screen or portion thereof with icon showing the claimed design.

The broken lines in the FIGURE show a display screen or portion thereof, and form no part of the claimed design.

The dot-dash broken lines in the FIGURE and the faded area within the dot-dash broken lines show portions of the icon that form no part of the claimed design.
